PUMPING DEVICE FOR MUSICAL INSTRUMENTS.

1,100,214.

Specification of Letters Patent.

Patented June 16, 1914.

Application filed December 26, 1912. Serial No. 738,510.

To all whom it may concern:

Be it known that I, THEODORE P. BROWN, a citizen of the United States, residing at Worcester, in the county of Worcester and 5 State of Massachusetts, have invented a new and useful Pumping Device for Musical Instruments, of which the following is a specification.

This invention relates to pneumatic operating means for musical instruments.

The principal object thereof is to provide an exceedingly simple and inexpensive means for resisting the torsional strain on the movable leaves of the bellows due to the 15 usual connection of said movable leaves at one edge thereof with the pedals that operate them.

Reference is to be had to the accompanying drawings in which—

20 Figure 1 is a front elevation of a portion of a pneumatic piano case with a preferred form of this invention; applied thereto; Fig. 2 is a sectional view on the line 2—2 of Fig. 1 showing the pedal and bellows in end elevation; Fig. 3 is a rear elevation of a modification of one part of the invention.

Referring first to Figs. 1, and 2, the invention is shown as applied to an ordinary type of pneumatic piano having the usual bellows comprising a fixed leaf 10 and a movable leaf 11. Two of these are shown and between them at the front are shown the two pedals 12 for operating them. For the purpose of supporting and connecting the 35 pedals so as to permit their ready operation, and especially to facilitate the assemblage thereof, a pair of bearings 13 are secured to a fixed part of the casing preferably to brackets 14 which support the bellows at the bottom. These two bearings 13 are arranged in alignment and the pedal connecting member is composed of a pair of cylindrical ends 15 located in axial alignment with each other, and supported by these 40 bearings. A pair of arms 16 extend from these ends laterally and a central portion 17 connected with them is parallel with the ends 15. This member 17 consists, if desired, of a single piece in which case the 45 whole supporting member will comprise a single integral piece, but for convenience in assembling, I prefer to make the member 17 in two detachable parts. Each of these 50 parts of the member 17 is simply cylin-

drical. They are connected by a larger tube 55 18 into the opposite ends of which the two parts of the member 17 extend, so as to form a telescoping joint. When the parts are assembled pins 19 are inserted to hold them in position. The two ends of the tube 18 60 can conveniently serve to engage against the ends of a set of bearing members 20 located at the lower ends of the pedals for the reception of the members 17, and it is through this construction that the pedals are pivoted 65 on the members 17. The latter are provided with the usual feet 21.

For the purpose of operating the movable leaves of the bellows, links 22 are shown, one at the outer edge of each of the pedals connected with brackets 23 on the respective movable leaves 11. It will be understood, of course, that as these parts 22 and 23 are located at the sides of the bellows they will tend to turn the bellows on a substantially 70 vertical axis. For the purpose of resisting the torsional strain thus produced, the following mechanism is shown: On the back of each movable leaf are bearings 25 which support a shaft 26. This shaft is provided 75 with two legs 27 on the ends both beyond the edges of the movable leaf. These parts 26 and 27 may conveniently be in a single U-shaped piece. The ends of these legs are connected with a fixed part of the instrument preferably the fixed leaf 10. For this purpose, in Figs. 1 and 2 the fixed leaf is shown as provided with a pair of pivoted links 28, each pivotally connected with the 80 end of one of the legs 27.

In the form shown in Fig. 3, the fixed leaf is shown as provided with a pair of bearings 30 supporting a shaft 31 having two arms 32 projecting from its ends and provided at their ends with axially aligned projections 33 95 for pivotal connection with the legs 27. Both arrangements are devised for the purpose of resisting the torsional strain above mentioned, and securing a perfect motion of the movable leaf of the bellows, that is, a 100 motion in which both sides move equally. In this way the tendency to distort the hinge at 35 is very materially reduced, and the repairs necessary to keep the bellows in order are also lessened, while the operation of the 105 device is rendered more even, uniform, and effective.

Although I have illustrated and described

only two embodiments of the invention, I am aware of the fact that modifications can be made therein by any person skilled in the art without departing from the scope of the invention as expressed in the claims. Therefore, I do not wish to be limited to all the details of construction herein shown and described, but

What I do claim is:—

- 10 1. In a musical instrument the combination with a bellows having a movable leaf, of means connected with one edge of the movable leaf for operating it, and means connected to the movable leaf and to some relatively fixed part for resisting the torsional strain due to the operation of the movable leaf by said operating means.
- 15 2. The combination with a bellows having a fixed and a movable leaf, and means for operating the movable leaf, of a member pivoted on the movable leaf and having arms at the two edges thereof and connected with the fixed leaf for resisting the torsional strain due to the operation of the movable leaf.
- 20 3. The combination with a bellows having a movable leaf, and means for operating the movable leaf, of a U-shaped member extend-

ing across the movable leaf and pivoted thereon, the two legs thereof projecting beyond the edges of the movable leaf, and means for connecting the ends of said legs with a fixed part of the device.

4. The combination with a bellows having a movable leaf, and means for operating the movable leaf, of a U-shaped member extending across the movable leaf and pivoted thereon, the two legs thereof projecting beyond the edges of the movable leaf, and pivoted links connecting the ends of said legs with a fixed part of the device.

5. The combination with a bellows having a fixed and a movable leaf, and means for operating the movable leaf, of an oscillatable member extending across the movable leaf and pivoted thereon, and having two legs at its ends projecting beyond the edges of the movable leaf, and means for connecting the ends of said legs with the fixed leaf.

In testimony whereof I have hereunto set my hand, in the presence of two subscribing witnesses.

THEODORE P. BROWN.
